[57] CLAIM

The ornamental design for a jewelry cleaner, as shown and described.

DESCRIPTION

FIG. 1 is a front elevational view of a jewelry cleaner showing my new design;

FIG. 2 is a right side elevational view thereof;

FIG. 3 is a left side elevational view thereof;

FIG. 4 is a rear elevational view thereof;

FIG. 5 is a bottom plan view thereof;

FIG. 6 is a top plan view with a cover removed showing a basket inserted within the jewelry cleaner;

FIG. 7 is a top plan view with the cover and the basket removed; and,

FIG. 8 is a top plan view of the jewelry cleaner in an assembled condition.

The cover in FIGS. 6 and 7 and the basket in FIG. 7 are shown removed for clarity of illustration.

FIG. 1

FIG. 3

FIG. 2

FIG. 4

FIG. 5

FIG. 6

FIG. 7

FIG. 8
